MOTOR AND IGNITION SAFETY CONTROL
SYSTEM FOR LIQUID FUEL BURNERS

Neal J. Mosely, Mount Lebanon Township, Allegheny County, Pa., assignor to Detroit Controls Corporation, a corporation of Michigan

Application November 27, 1951, Serial No. 258,339

8 Claims. (Cl. 158—28)

1

This invention relates to new and useful improvements in control systems for liquid fuel burners and more particularly to a "primary" control system which is constructed of a minimum number of control parts.

In the past, many types of control systems, devices and circuits have been proposed for controlling the operation of liquid fuel burners, but substantially all of those have involved the use of very complicated circuits involving many switches, relays, and complicated timing mechanisms. In this invention there is provided a control system having a minimum number of operating control parts to provide for maximum simplicity and efficiency in operation.

Accordingly, it is one object of this invention to provide a new and improved control circuit for liquid fuel burners.

Another object is to provide a control circuit for liquid fuel burners having as few control switches and as simple a timing mechanism as possible.

Another object is to provide a liquid fuel burner control system which will turn on a burner motor and ignition, after a predetermined time turn off the ignition, and if no flame occurs in the burner by the time the ignition is turned off, will, after a predetermined further period of time, turn off the burner motor, all with a minimum number of control switches and circuits.

Another object is to provide a liquid fuel burner control circuit and control devices therefor which are simply and inexpensively constructed and assembled.

Other objects will become apparent from time to time throughout the specification and claims as hereinafter related.

This invention comprises the new and improved construction and combination of parts and their operating relationship each to each, which will be described more fully hereinafter and the novelty of which will be particularly pointed out and distinctly claimed.

In the accompanying drawing, to be taken as part of this specification, there is clearly and fully illustrated a preferred embodiment of this invention, in which drawing the figure shows in more or less diagrammatical form a control system for liquid fuel burners which is the subject of this invention.

Referring to the drawing by characters of reference there is shown a liquid fuel burner 101 having a burner motor 102 and an electric spark ignition 103. There is provided a transformer 104 having a primary 105 supplied from a high

2

voltage power source 106 and having a secondary coil 107. From the high voltage power source 106 the wire 108 connects to the contact arm 118 of a switch 119. The switch 119 comprises contact arms 118 and 120 carrying normally closed contacts 121 and 122, respectively, biased into initial engagement with each other. From the wire 108, the wire 116 connects to one side of the burner motor 102. From the contact arm 120 of the switch 119 a wire 123 connects to one end portion of the primary coil 124 of the ignition transformer 125. The ignition transformer 125 has a secondary coil 126 and wires 127 and 128 leading therefrom to the spark ignition 103. The other end portion of the ignition primary coil 124 is connected as at 129 to a return wire 130 from the burner motor 102 which is connected to the contact arm 131 of a switch 132. The switch 132 comprises contact arms 131 and 133 carrying contacts 134 and 135, respectively. The contact arm 133 is biased toward engagement of the contacts 134 and 135 but is restrained by engagement with a stop 166. The contact arm 131 is biased away from the contact arm 133 and is engaged by a thrust transmitting member 141. The contact arm 133 is connected by a wire 136 back to the other side of the high voltage power source 106. There is provided a snap mechanism 137 which is co-operable with the contact arm 133 and is operable upon predetermined movement in one direction to snap the arm 133 away from the arm 131. The snap mechanism 137 may be any suitable snap mechanism, but for the purposes of this disclosure is shown as an overcenter spring 138 and a suitable adjustment mechanism 139 therefor such as an adjustable screw 139. The adjustment screw 139 is operable to vary the relation of the spring 138 to the contact arm 133. The compressive force of spring 138 biases the contact arm 133 toward the contact arm 131 and into engagement with the stop 166. A reset member 140 is provided in overlying relation to the contact arm 133 to reset the same from an overcenter snapped open position. The contact arm 118 is biased for movement along with the contact arm 120 of the switch 119 which is moved by a suitable thrust transmitting member 142 and which transmits movement through member 141 to the contact arm 131 of the switch 132. There is provided a timing means 144, which comprises a bi-metal member 145 which is operated in accordance with the heat output of a resistance heater 146 and the force against which the member 145 must work. Since the bimetal member 145 warps at a rate which is determined by the

rate of heat input and the force against which it works, and since the heating of the bimetal by the resistance heater 146 is a function of the time that the heater was energized, it is apparent that the timing operation of the bimetal may be adjusted by varying either the distance which it must move or the force against which it must work. The screw 139 is operable to adjust the compressive force exerted by the spring 138 and thus varies the timing operation by varying the force against which the bimetal must work. If the compression of spring 138 is increased the bimetal must warp with a greater force, which requires a longer heating period. Similarly the spring 138 could be adjusted to vary the snap point of the arm 133 by varying the distance which that arm must move before snapping over center. The resistance heater 146 is connected to one side of the transformer secondary 107 by a wire 148 and is connected by wires 149, 150 and 151 to the fixed contacts 152 and 153 of a single-pole, double-throw switch 154. A resistor 155 is provided in circuit between the wires 149 and 151 to modify the operation of the resistance heater 146 for the timing means 144. The movable pole 156 of the switch 154 carries contacts 157 and 158 cooperable with fixed contacts 152 and 153, respectively, and is connected by wire 159 to a fixed contact 160 of a room thermostat 161. The switch operating pole 156 of the switch 154 is operated by a suitable flame responsive means 162 such as a bi-metal helix positioned for response to flame temperature in the burner stack 163. The room thermostat 161 has a suitable temperature responsive member such as a bi-metal 164 connected by a wire 165 to the other side of the transformer secondary 107 and carries a movable contact 166 cooperable with the fixed contact 160.

Operation

In operation this system functions generally as follows:

The resistance heater 146 and bi-metal member 145 co-operate to form an electro-thermal timer for operating the switches 119 and 132. The timer 144, since it performs its timing function in accordance with the heat output of the heater 146, must be positioned away from the burner 101 in such a position that it is not affected appreciably by burner temperature. When the room thermostat contacts 160 and 166 are closed calling for heat, a circuit is completed from the transformer secondary 107 through wire 148, resistance heater 146, wire 149, wire 150, contacts 152 and 157 of switch 154, wire 159, contacts 160 and 166 of the thermostat 161, thermostat blade 164, and wire 165, completing the connection to the transformer secondary 107. With this circuit completed, the heat output of the heater 146 will cause the bi-metal 145 to move at a rate dependent upon the heat output of the heater 146, the type of bi-metal used in the member 145, and the resistance against which the bi-metal member 145 must operate. As the bi-metal member 145 is moved upwards, it moves the thrust member 142 against the contact arm 120 and thus moves the contact arm 131 to move the switch contact 134 into engagement with contact 135. When the contacts 134 and 135 are brought into engagement, a high voltage circuit 70 is completed from the power source 106 by way of wire 108, contact blade 118, contacts 121 and 122, and contact blade 120 to wire 123 connected to the ignition 124. From wire 108 adjacent the switch 119 the circuit divides and part is con-

nected through the ignition and part through the burner motor. The circuit through the burner motor extends from wire 108 by way of wire 116. The circuit through the ignition was previously described. The burner and ignition circuits join again at point 129 on wire 130 which connects to contact arm 131 of the switch 132. The circuit is completed back to the other side of the high voltage power source through contact arm 131, contacts 134 and 135 when closed, contact arm 133 and wire 136. At this stage of the operation, with both switches closed, both the burner motor and ignition are energized and in the normal course of operation flame should occur in the burner. After the predetermined time (determined by the physical constants of the heater 146 and bi-metal 145), the contact arms 118 and 120 of the switch 119 will be moved until the contact arm 118 engages the stop 143, and upon further movement the contacts 121 and 122 are separated, thus breaking the circuit to the ignition transformer 124. If at this point no flame has occurred in the burner, the bi-metal member 145 of the timer 144 will continue to move, and after predetermined further movement the contact arms 131 and 133 of the switch 132 will be moved to an overcenter position relative to the snap mechanism 137 and the contact arm 133 and switch contact 135 will move away from the contact 134 with a snap movement, thus breaking the circuit to both the burner motor 102 and ignition transformer 124. If flame occurs in the burner 101 after the closing of the switch contacts 134 and 135 of switch 132, and prior to the re-opening of those contacts, the flame responsive bi-metal 162 will move the contact pole 156 of the double-throw switch 154 and open the contacts 152 and 157 and close the contacts 153 and 158 to place the resistor 155 in series circuit with the resistance heater 146 for the bi-metal member 145. When the resistor 155 is placed in series with the resistance heater 146, the voltage drop through the resistor 146 is reduced to a point such that the heat output thereof to the bi-metal member 145 is sufficient to maintain the same in an actuated position between the point at which the contacts 121 and 122 of switch 119 are opened and the point at which the switch 132 is snapped open. It will be seen then that in normal operation when the system is required to produce heat, the timing means first causes the switches to be placed in a position to energize both the ignition and burner motor. After a predetermined time the ignition switch is opened and the burner motor circuit remains on. If flame has occurred in the burner by this time, the timer mechanism will hold the switches in this position. Upon de-energization, the ignition switch will first close and then the switch 132 controlling both the burner and ignition will reopen (by engagement of contact arm 133 with stop member 166). The closing of the ignition switch just prior to de-energization of the system will cause a momentary ignition at this time and will consume any residual combustible gases left in the burner. On the other hand, if flame does not occur in the burner by the time the ignition switch is opened, the timer mechanism moves the switch 132 until the same is snapped open, as previously described, and the burner and ignition are both shut down by that operation. After the switch 132 has been snapped open, it is necessary that the contact arm 133 and contact 135 be reset manually from this safety position and the reset button 140 is provided for that purpose. It should also be

noted that the snap mechanism 137 includes an adjustment means such as the screw 139 for the overcenter spring 132 to vary its relation to the contact arm 133 and thus vary the time required to move to a safety snapped open position.

From the foregoing descriptions of the system disclosed herein, it is seen that there is here provided a very simple control system for a liquid fuel burner having a very simple timing mechanism and having considerably less than the usual number of control switches and other control parts therefor.

While there has been described herein only a form of this invention, it will be obvious to those skilled in the art that other modifications of this system are possible without departing from the scope and intent of this invention as defined in the appended claims.

Having thus described the invention, what is claimed and is desired to be secured by Letters Patent of the United States is:

1. In a burner control system, a liquid fuel burner, a burner motor and electric circuit therefor, an electric ignition means and circuit therefor, a first switch having initially closed contacts in said ignition circuit, a second switch connected in series with said first switch and having contacts in both said motor and said ignition circuits, said second switch having a contact arm and a snap mechanism cooperable therewith operable to cause the same to be snapped to an open position after actuating movement in one direction through a predetermined range, means cooperable with said first switch to cause the same to be opened after movement less than said predetermined range, electric timing means for actuating said switches, a circuit for said timing means, said timing means being arranged to actuate said switches sequentially so that said second switch is closed first, after a predetermined time said first switch is opened, and upon actuation through said predetermined range said second switch is reopened with a snap movement, means controlling energization of said timing means circuit, and means operable to stop said timing means at a point of actuation subsequent to opening said first switch and prior to reopening said second switch.

2. In a burner control system, a liquid fuel burner, a burner motor and electric circuit therefor, an electric ignition means and circuit therefor, a first switch having initially closed contacts in said ignition circuit, a second switch connected in series with said first switch and having contacts in both said motor and said ignition circuits, said second switch having a contact arm and a snap mechanism cooperable therewith operable to cause the same to be snapped to an open position after actuating movement in one direction through a predetermined range, means cooperable with said first switch to cause the same to be opened after movement less than said predetermined range, electric timing means for actuating said switches, a circuit for said timing means, said timing means being arranged to actuate said switches sequentially so that said second switch is closed first, after a predetermined time said first switch is opened, and upon actuation through said predetermined range said second switch is reopened with a snap movement, means controlling energization of said timing means circuit, and means responsive to the occurrence of flame in said burner to stop said timing means at a point of actuation subsequent

to opening said first switch and prior to reopening said second switch.

3. In a burner control system, a liquid fuel burner, a burner motor and electric circuit therefor, an electric ignition means and circuit therefor, a first switch having initially closed contacts in said ignition circuit, a second switch connected in series with said first switch and having initially open contacts in both said motor and said ignition circuits, said second switch having a contact arm and a snap mechanism cooperable therewith operable to cause the same to be snapped to an open position after actuating movement in one direction through a predetermined range, means cooperable with said first switch to cause the same to be opened after movement less than said predetermined range, electric timing means reversibly actuated for actuating said switches, a circuit for said timing means, said timing means actuating said switches in said one direction upon energization and in the other direction upon de-energization, said timing means being arranged to actuate said switches sequentially so that said second switch is closed first, after a predetermined time said first switch is opened, and upon actuation through said predetermined range said second switch is reopened with a snap movement, a thermostatic switch responsive to the temperature of the space heated by said burner to control energization of said timing means circuit, and means responsive to the occurrence of flame in said burner to stop said timing means at a point of actuation subsequent to opening said first switch and prior to reopening said second switch.

4. In a burner control system, a liquid fuel burner, a burner motor and electric circuit therefor, an electric ignition means and circuit therefor, a first switch having initially closed contacts in said ignition circuit, a second switch connected in series with said first switch and having initially open contacts in both said motor and said ignition circuits, said second switch having a contact arm and a snap mechanism cooperable therewith operable to cause the same to be snapped to an open position after actuating movement in one direction through a predetermined range, means cooperable with said first switch to cause the same to be opened after movement less than said predetermined range, electric timing means comprising a bimetallic heat motor and resistance heater therefor, reversibly actuated upon heating and cooling for actuating said switches, a circuit for said resistance heater, said timing means actuating said switches in said one direction upon energization and in the other direction upon de-energization, said timing means being arranged to actuate said switches sequentially so that said second switch is closed first, after a predetermined time said first switch is opened, and upon actuation through said predetermined range said second switch is reopened with a snap movement, a thermostatic switch responsive to the temperature of the space heated by said burner to control energization of said resistance heater circuit, and means responsive to the occurrence of flame in said burner to reduce the heat output of said resistance heater to said bimetallic heat motor to a point operable to maintain the same in an actuated position less than the predetermined range of movement required for reopening said second switch.

5. In a burner control system, a liquid fuel burner, a burner motor and electric circuit there-

for, an electric ignition means and circuit therefor, a first switch having initially closed contacts in said ignition circuit, a second switch connected in series with said first switch and having initially open contacts in both said motor and said ignition circuits, said second switch having a contact arm and a snap mechanism cooperable therewith operable to cause the same to be snapped to an open position after actuating movement in one direction through a predetermined range, means cooperable with said first switch to cause the same to be opened after movement less than said predetermined range, electric timing means comprising a bimetallic heat motor and resistance heater therefor, reversibly actuated upon heating and cooling for actuating said switches, a circuit for said resistance heater, said timing means actuating said switches in said one direction upon energization and in the other direction upon de-energization, said timing means being arranged to actuate said switches sequentially so that said second switch is closed first, after a predetermined time said first switch is opened, and upon actuation through said predetermined range said second switch is reopened with a snap movement, a thermostatic switch responsive to the temperature of the space heated by said burner to control energization of said resistance heater circuit, parallel circuits connected in series with said resistance heater, a resistor in one of said parallel circuits for reducing the heat output of resistance heater to a point such that said timing

30

- means heat motor cannot move through said predetermined distance to reopen said second switch, a double throw switch connected to said parallel circuits for switching between them, and means responsive to the occurrence of flame in said burner to actuate said double throw switch to connect the circuit including said resistor in series connection with said resistance heater.
6. A burner control system as defined in claim 5 including a movable reset member cooperable with said second switch contact arm for resetting the same from said snapped open position.
7. A burner control system as defined in claim 5 including means to adjust said snap mechanism to vary the time of energization of said timing means required to snap open said second switch.
8. A burner control system as defined in claim 6 including means to adjust said snap mechanism to vary the time of energization of said timing means required to snap open said second switch.
